UNITED STATES PATENT OFFICE.

HARRY GEORGE ALBRECHT, OF BROOKLYN, NEW YORK.

MEDICINE-CABINET.

1,307,949.

Specification of Letters Patent. Patented June 24, 1919.

Application filed December 21, 1915. Serial No. 68,078.

To all whom it may concern:

Be it known that I, HARRY G. ALBRECHT, a citizen of the United States, residing at Brooklyn, in the county of Kings, State of New York, have invented certain new and useful Improvements in Medicine-Cabinets; and I do hereby declare the following to be a full, clear, and exact description of the invention, such as will enable others skilled in the art to which it appertains to make and use the same.

The present invention is directed to improvements in medicine cabinets, and has for its object to provide a device of this character formed entirely from sheet metal.

A further object of the invention is to provide a cabinet of this type so constructed that the shelves thereof can be adjusted vertically, and further to provide a compartment for storing poisonous medicine, access to which being had only by a person having a key for the door of the compartment.

A still further object of the invention is to provide a sheet metal cabinet so constructed that the same can be readily assembled, and when the parts thereof are assembled the same will resemble a cabinet formed from wood.

With these and other objects in view, this invention resides in the novel features of construction, formation, combination and arrangement of parts to be hereinafter more fully described, claimed and illustrated in the accompanying drawing, in which:

Figure 1 is a front view of the cabinet.

Fig. 2 is a similar view with the door removed.

Fig. 3 is a sectional view on line 3—3 of Fig. 1.

Fig. 4 is a similar view on line 4—4 of Fig. 1.

Fig. 5 is a sectional view on line 5—5 of Fig. 2.

Referring to the drawing 1 indicates a casing which is formed from suitable sheet metal and comprises a back 2, sides 3 and top and bottom 4 and 5, respectively, all of which having bolted thereto angle brackets 6 which are adapted to be bolted to the trimming strips 7, which are also formed from sheet metal and have their adjacent ends mitered, as at 8.

A false bottom 9 is provided and has its ends terminating in downwardly extended flanges 10 which are riveted to the adjacent

sides 3 of the casing, said bottom forming in conjunction with the bottom 5 a compartment 11. The false bottom 9 is of less width than the sides 3 of the casing so that the angle strips 12 may be riveted to the sides, 60 said strips forming in conjunction with the vertical side trimming strips 7, guides 13 for slidably engaging the ends of the door 14, said door having a lock 15 carried thereby which is adapted to coöperate with the keeper 16 carried by the bottom 5, whereby the door can be locked when desired. Thus it will be seen that a compartment has been provided wherein poisonous medicine can be stored, while harmless medicine and 70 toilet articles can be placed on the shelves 17, which are formed from sheet metal and have their ends adjustably engaged with the shoulders 18 formed by bending the metal strips 19 as shown, said strips being riveted to the sides 3 of the casing 1 and in pairs, thus providing sufficient bearing surface for the ends of the shelves.

Hingedly connected to one of the trimming strips 7 is a door 20, said door being 80 provided with a latch 21 which coöperates with the keeper 22 carried by the adjacent trimming strip 7, whereby the door can be fastened in its closed position.

The door has fixed to its outer surface 85 a frame 23 which supports the mirror 24. Fixed to the outer surface of the door is a thermometer 25.

From the foregoing description it will be seen that a thoroughly sanitary cabinet 90 has been provided since the same has been made wholly from sheet metal and can be readily cleansed. It will be further noted that the cabinet is so constructed that it can be placed in a cavity in a wall, and at which 95 time the trimming strips 7 will rest flush against the outer surface of the wall, or if desired the cabinet can be suspended in any suitable manner.

What is claimed is:

A cabinet including a casing having a top, sides and a bottom, a shelf mounted in said casing for forming a compartment therein and having downwardly extending flanges at its ends of less width than the sides of said casing, trimming strips secured to said sides and having their inner edges extending inwardly thereof, angle strips also secured to said sides and interposed between said flanges and trimming strips and forming 110

guide grooves in conjunction with the latter, a door mounted in said guide grooves, shoul-
dered strips also secured to said sides above
said angle strips, shelves adjustably mount-
ed on the shoulders of the last named strips,
and a door hinged to one of said trimming
strips for closing said casing.

In testimony whereof, I affix my signa-
ture, in the presence of two witnesses.

HARRY GEORGE ALBRECHT.
